CLAIM

Aug. 31, 2023 (CN) 202330563922.3

The ornamental design for an arc integrated smart tablet
phone camera device as shown and described.

(51) **LOC (15) Cl.** **16-01**

DESCRIPTION

(52) **U.S. Cl.**

FIG. 1 is a front, top, and right perspective view of an arc
integrated smart tablet phone camera device showing my
new design;

USPC **D16/214**

FIG. 2 is a front elevational view thereof;

(58) **Field of Classification Search**

FIG. 3 is a rear elevational view thereof;

USPC D8/300, 303, 306, 307, 321, 323, 324,

FIG. 4 is a left side elevational view thereof;

D8/325, 349, 363, 373, 394; D14/313,

FIG. 5 is a right side elevational view thereof;

D14/316, 317, 324, 341, 372, 375, 376,

FIG. 6 is a top plan view thereof;

D14/377, 432, 203.3, 203.5, 482, 224,

FIG. 7 is a bottom plan view thereof; and,

D14/217, 229, 250, 251, 345, 253;

FIG. 8 is a rear, bottom, and left perspective view thereof.

D16/200, 204, 206, 208, 211, 213–219,

D16/234, 235, 236, 237–250, 136;

(Continued)

D20/10, 41–43; D21/329, 330, 331, 333,

D21/385, 514

CPC F16M 11/00; F16M 11/06; F16M 11/08;

F16M 11/10; F16M 11/14; F16M 11/18;

F16M 11/20; F16M 11/041; F16M

11/105; F16M 11/2007; F16M 11/2014;

The broken lines shown in the drawings represent portions of the arc integrated smart tablet phone camera device that form no part of the claimed design.
